Filed Jan. 15, 1960, Ser. No. 59,059

Term of patent 14 years

(Cl. D4—2)

FIG. 1

FIG. 2

FIG. 3

FIG. 4

FIGURE 1 is a front perspective view taken from the top and right side of a cabinet top lavatory embodying my new design;

FIGURE 2 is a top plan view thereof;

FIGURE 3 is a front elevational view thereof; and

FIGURE 4 is a left side elevational view thereof.

The dominant features of my design reside in the portion shown in full lines.

The fragmentary broken-line representation of a cabinet shown in FIGURES 1, 3 and 4 is for purposes of illustration only.

I claim:

The ornamental design for a cabinet top lavatory, as shown and described.
